UNITED STATES PATENT OFFICE.

RICHARD SCHÜRMANN, OF ESSEN, GERMANY, ASSIGNOR TO FRIED. KRUPP AKTIEN-GESELLSCHAFT, OF ESSEN-ON-THE-RUHR, GERMANY.

GUN WITH LATERALLY-ADJUSTABLE BARREL.

Application filed September 7, 1920. Serial No. 408,745.

(GRANTED UNDER THE PROVISIONS OF THE ACT OF MARCH 3, 1921, 41 STAT. L., 1313.)

To all whom it may concern:

Be it known that RICHARD SCHÜRMANN, citizen of the German Republic, residing at 35 Isabellastrasse, Essen, Germany, has invented certain new and useful Improvements in Guns with Laterally-Adjustable Barrels, of which the following is a specification.

This invention relates to a gun with a gun barrel, which is adjustable in a lateral direction and the object of the invention is to materially accelerate the operation of pointing in the case of such a gun, when it is required to alter the angle which is made between the vertical planes passing through the sighting line and the longitudinal axis of the gun barrel. An alteration of this kind is necessary in order, for example, to allow for the lateral deviation of the projectile which takes place owing to its rotation or through the action of a side wind, or when firing at a target which moves in a lateral direction at a comparatively high speed, to place the point at which the projectile is to strike laterally in front of the target. To this end the sighting device is arranged on a part of the gun partaking in each lateral movement of the gun barrel and is adjustable relatively to this part of the gun in lateral direction by means of an adjusting gear, which is in such a positive connection with an operating member of the traversing gear that the gun barrel and the sight carrier rotate through the same angle, but in opposite directions, when the operating member is rotated.

The invention will be further described with reference to the accompanying drawings which show a construction of the invention:

Figure 1 is a side elevation, partly in section, of those parts of the gun affected by the present invention.

Figure 2 is the rear elevation corresponding to Figure 1, also partly in section.

Figure 3 is a section on the line 3—3 of Figure 1, looking from above.

Figure 4 is a section on the line 4—4 of Figure 1 on an enlarged scale, looking from the right.

Referring to the drawings, parts of the

apparatus already known and which do not form part of the present invention will be firstly described.

The slide B, which guides the gun barrel A is supported on an upper carriage C and is connected thereto by means of a vertical pin b', which can be traversed in an aperture in the upper carriage and by a curved dovetail-shaped rib b² coaxial with the axis 55 of the pin b'. The rib b² is itself guided in a correspondingly shaped groove c' in the upper carriage, which is pivotally mounted by means of two horizontal trunnions in an under carriage D. Between the upper carriage C and the under carriage D is interposed a screw elevating gear, which can be operated in the well known way by means of two hand wheels E and F, which can be rotated independently of each other. One 60 of these two hand wheels (E) is mounted on the under carriage and the other one (F) in two bearings c² on the upper carriage C. On the free end of a lateral arm B³ mounted in the vicinity of the breech end A' of the 65 gun barrel on the slide B is rigidly secured a drum b⁴, in which is pivotally mounted a second drum G carried on a horizontal pin b⁵. This drum G, which forms the part of the sighting device, which can be adjusted 70 to correspond to the range of the target, has a member g', which projects through an opening b⁶ in the drum b⁴ and carries the sighting telescope J. The inner drum G is adjusted to the angle corresponding to the 75 range of the target by a worm H, which cooperates with a series of teeth cut in the outer surface of the drum G and when revolved rotates the drum G and with it the sighting telescope J about the axis of the pin 80 b⁵. The angular position imparted to the sighting telescope J by the worm H is read off on a range graduation h² located on the extended shaft h' of the worm H along a helical groove and a reading off mark (not 85 shown) movable longitudinally in the direction of the axis of the shaft h'. From the shaft h' a partially jointed and at the same time telescopically extensible shaft connection leads to the hand wheel F of the elevat- 90 ing gear. The whole of the arrangement is 95 at the same time so devised that, by rotating

the hand wheel F, the gun barrel A and (by means of the above mentioned shaft connection and the gearing H g^2) the sighting telescope J are adjusted through the 5 same angle but in the opposite direction and by rotating the hand wheel E the gun barrel and the sighting telescope J are mutually adjusted and in the same direction vertically.

The construction and arrangement of the 10 parts of the gun so far described are known and do not form part of this invention.

According to the present invention the traversing gear for swinging the slide round about the axis of the pin b' consists of a series of worm teeth h^2 on the rib b^2 concentric with this pin b' a worm k' engaging with the said worm teeth on the rib b^2 and mounted on a hollow shaft K and two operating devices for the worm k' .

20 The first operating device (see particularly Figures 3 and 4) for the worm k' consists substantially of a shaft M mounted on the upper carriage and carrying a hand wheel m' and a worm m^2 , a worm wheel n' gearing into the worm m^2 and mounted on the end of a traverse shaft N likewise carried on the upper carriage C and two spur wheels n^2 , which are mounted to rotate loosely on two crank pins n^3 on the shaft N 25 and located diametrically opposite each other. These two spur wheels co-operate with a spur wheel k^2 , which is mounted on one end of the hollow shaft K slidden over the shaft N. The lateral angular position 30 imparted to the gun barrel A by means of the hand wheel m' can be read off on an angle graduation (not shown), which is arranged along a helical groove in the shaft M and which is opposite a reading off mark 35 (not shown) adjustable in the direction of this shaft.

The second operating device consists substantially of a hand wheel p' likewise mounted on the upper carriage, a shaft P, 40 a worm p^2 , a wheel Q provided with a series of worm teeth q' and an internal series of spur teeth, the spur wheels n^2 gearing into the internal teeth q^2 and the spur wheel k^2 on the hollow shaft K co-operating with the 45 spur wheels n^2 . The two worm gears m^2 n' and p^2 q' are self-locking.

Upon the end of the shaft N next to the 50 wheel Q is mounted a bevel wheel n^4 , which gears with a second bevel wheel r' , the shaft R of which is likewise pivotally mounted on the upper carriage C.

The sighting telescope J, which is mounted on a part J' , which acts as a bearing for it on the cover of a hollow cylindrical enlargement g^3 of the member g' is provided with a pin i^2 , which rotates in a vertical aperture in the cover of the enlargement g^3 and is provided with a worm wheel i^3 placed inside the hollow cylindrical enlargement.

60 With the worm wheel i^3 gears a worm s' the

shaft S of which is rotatably mounted in the wall of the cylindrical enlargement g^3 . The shaft S carries on its free end a bevel wheel s^2 with which a second bevel wheel t' co-operates. The bevel wheel t' is mounted on the free end of a shaft T likewise mounted on the enlargement g^3 and positively connected by a jointed and telescopically extensible shaft connection T^2 T^2 with the bevel wheel r' . The whole of the arrangement and 70 the ratio of transmission of the gears n^4 r' T^2 T^2 T t' S^2 S s' i^3 and n^2 k^2 K k' b^7 are so arranged that when the hand wheel m' is rotated the gun barrel A and the sighting telescope J rotate through the same angle 80 but in the opposite direction, about the axes of the vertical pins b' and i^2 .

The manner, in which the gun above described is elevated to correspond to the position and range of the target by turning the 85 hand wheels E and F, is already known and need not therefore be especially described.

In order to adjust the sighting line and the longitudinal axis of the gun barrel A in a lateral direction e. g. to a laterally moving target, the operating device operated by the hand wheel p' of the traversing gear is employed.

When the said operating device is rotated, the slide B and with it also the gun barrel A 95 is rotated about the axis of the vertical pin b' relatively to the upper carriage C by means of the gearing P p^2 q' Q q^2 n^2 k^2 K k' b^7 , the shaft N remaining stationary by reason of the automatic locking of the gearing m^2 n' . 100 This traversing movement of the gun barrel A is taken up by the sighting line, as the sighting telescope J, which determines the direction of the sighting line, is arranged on the arm B^3 mounted on the slide B. As soon as therefore the sighting line points to the target on the rotation of the hand wheel p' , the longitudinal axis of the gun barrel A is also pointed in a lateral direction on the target.

In order to transmit to the gun barrel the adjustment corresponding to the lateral deviation or drift of the projectile for example, the hand wheel m' is employed.

When this hand wheel m' is rotated, the 115 slide B and with it the gun barrel A and the sighting device mounted on the arm B^3 will be rocked by means of the gearing M m^2 n' N n^3 n^2 k^2 K k' b^7 about the axis of the vertical pin b' relatively to the upper carriage 120 C, the wheel Q remaining stationary by reason of the automatic locking of the gear p^2 q' . The movement of the shaft N is simultaneously transmitted by means of the gearing n^4 r' R T^3 T^2 T T' s^2 S s' i^3 to the 125 sighting telescope J in such a way that it rotates about the axis of the vertical pin i^2 through the same angle but in the opposite direction to the gun barrel. In consequence thereof the sighting line remains parallel 130

with its former position, while the gun barrel has imparted to it the adjustment which corresponds to the drift of the projectile.

The reading off takes place on the angle graduation (not shown) arranged on the shaft M and the corresponding reading off mark.

As will be quite clear without further description, the hand wheel m' can also be used when firing at laterally moving targets to lay the point of impact of the projectile laterally in front of the target to correspond to the speed of movement of this latter.

As the sighting line remains parallel with its former position during the adjusting movements of the gun barrel to correspond to the drift of the projectile or a lateral shifting of the point of impact of the projectile, it never loses its direction on the target when the gun barrel is being adjusted laterally, and it is therefore impossible for the target to get out of the field of view of the telescope. The said fact enables moreover, under otherwise equal conditions the time required for the lateral adjusting operation to be considerably reduced and the rate of fire of the gun to be consequently increased, which fact is of great importance particularly when firing at moving targets.

30 Claims:

1. In a gun having a gun barrel adjustable in lateral direction, a traversing gear for laterally adjusting the gun barrel and a driving member for operating the traversing gear, the combination with a sighting device arranged to partake on each lateral adjustment of the gun barrel and comprising a sighting means carrier adjustable in lateral direction relatively to the gun barrel and a gear for effecting the lateral adjustment of the sighting means carrier of means positively connecting the driving member of said traversing gear to said sighting means adjusting gear, whereby the gun barrel and the sighting means carrier may be rotated through the same angle but in opposite direction when said driving member of the traversing gear is operated.

2. In a gun having a gun barrel adjustable in lateral direction and a traversing gear for laterally adjusting the gun barrel, a sighting device arranged to partake on each lateral adjustment of the gun barrel and comprising a sighting means carrier adjustable in lateral direction relatively to the gun barrel and a gear for effecting the lateral adjustment of the sighting means carrier, two driving members for operating said traversing gear independently of each other and means positively connecting said sighting means adjusting gear to one of said driving members, whereby the gun barrel and the sighting means carrier may be rotated through the same angle but in opposite direction when the driving member positively connected to

the sighting means adjusting gear is operated and the other driving members is held stationary.

3. In a gun having a gun barrel adjustable in lateral direction and a traversing gear for laterally adjusting the gun barrel, a sighting device arranged to partake on each lateral adjustment of the gun barrel and comprising a sighting means carrier adjustable in lateral direction relatively to the gun barrel and a gear for effecting the lateral adjustment of the sighting means carrier, two driving members for operating said traversing gear, means positively connecting said sighting means adjusting gear to one of said driving members, a planetary gearing having two coaxial central wheels adapted to be rotated independently of each other, a bridge member rotatable about the same axis as said central wheels and planetary wheels carried by said bridge member and engaging said central wheels, means positively connecting each of said driving members to one of the three first-named members of the planetary gearing and means positively connecting the third member to the traversing gear of the gun barrel, whereby the gun barrel and the sighting means carrier may be rotated through the same angle but in opposite direction when the driving member positively connected to the sighting means adjusting gear is operated and the other driving member is held stationary.

4. In a gun having a gun barrel adjustable in lateral direction and a traversing gear for laterally adjusting the gun barrel, a sighting device arranged to partake on each lateral adjustment of the gun barrel and comprising a sighting means carrier adjustable in lateral direction relatively to the gun barrel and a gear for effecting the lateral adjustment of the sighting means carrier, two driving members for operating said traversing gear, a planetary gearing having two coaxial central wheels adapted to be rotated independently of each other, a bridge member rotatable about the same axis as said central wheels and planetary wheels carried by said bridge member and engaging said central wheels, means positively connecting said bridge member to one of said driving members and to the sighting means adjusting gear and means positively connecting the other driving member to one of said central wheels and the traversing gear of the gun barrel to the other central wheel, whereby the gun barrel and the sighting means carrier may be rotated through the same angle but in opposite direction when the driving member positively connected to the sighting means adjusting gear is operated and the other driving member is held stationary.

RICHARD SCHÜRMANN.
